US00D452245B1

(12) **United States Design Patent** (10) Patent No.: **US D452,245 S**
Wallace et al. (45) Date of Patent: **** Dec. 18, 2001**

(54) **PORTABLE MEMORY CARD FOR STORAGE OF PERSONAL INFORMATION**

(75) Inventors: **Robert F. Wallace**, Sunnyvale; **Robert C. Miller**, San Jose, both of CA (US)

(73) Assignee: **SanDisk Corporation**, Sunnyvale, CA (US)

(**) Term: **14 Years**

(21) Appl. No.: **29/141,407**

(22) Filed: **May 4, 2001**

Related U.S. Application Data

(62) Division of application No. 29/109,687, filed on Aug. 19, 1999, now Pat. No. Des. 442,598.
